GOLF PUTTING PRACTICE DEVICE

Robert C. Eldredge, Webster City, Iowa, assignor to
Stewart H. M. Lund, Webster City, Iowa

Application February 21, 1956, Serial No. 566,967

3 Claims. (Cl. 273—177)

This invention relates to games and game equipment, and more particularly to a golf-type game and equipment therefor.

An object of this invention is to provide a novel game and equipment therefor which simulates the well-known game of golf in manner of play as well as type of equipment, yet which employs comparatively inexpensive equipment and which requires neither the extended area nor the permanent installation of a golf course.

Another object is to provide a golf-type game adapted to be played out of doors, as on lawns, drives and other ground areas, as well as indoors on carpets and other floor areas.

Still another object is to provide equipment for a golf-type game which can be quickly and easily laid out for play without the necessity of digging or otherwise providing holes in the ground or floor, and which can with equal ease and facility be gathered up and compactly boxed for storage.

A further object is to provide a golf-type game in which the participants can experience the enjoyment and exercise of a full swing at a playing ball with a playing club without requiring an extensive playing area and with a minimum of hazard to other persons or property.

A still further object is to provide game equipment including a plurality of similar goal structures or "holes" which are adapted to be used as a series of holes laid out in desired stations, or to be used in a number less than all when either space limitations or personal preferences so dictate.

Yet another object is to provide game equipment including a plurality of similar hole structures which are adapted to be placed in stations independent of any set pattern for the game course, and in a number including all or less than all of the hole structures in a game set, so as to lend itself to either space limitations or personal preferences as to the layout and size of the course.

A further object is to provide novel multi-directional hole structures for a golf-type game which are inexpensive to manufacture, and which comprise a simple, non-mechanical target for golf-type games.

A further object is to provide hole structures for a game, which are adapted to be used in plural to prescribe a course of play, as well as individually for putting practice, and which have means for generally retaining a playing ball within the hole once the ball is projected into the latter.

Another object is to provide game equipment for a golf-simulating game, which is simple yet sturdy of construction, and adapted for use not only by family groups, but by playground and recreational departments as well.

Other objects and advantages of this invention will appear from the description hereinafter set forth, taken in connection with the appended drawings, in which:

Figure 1 is a perspective view of one hole structure of my invention, with a playing ball shown therewith;

Fig. 2 is an enlarged vertical sectional view taken on line 2—2 of Fig. 1;

2

Fig. 3 is an enlarged horizontal sectional view taken on line 3—3 of Fig. 1;

Fig. 4 is a perspective view of a club of my invention;

Fig. 5 is an enlarged fragmentary sectional view taken on line 5—5 of Fig. 4;

Fig. 6 is a perspective view of the case for a set of my game equipment; and

Fig. 7 is an enlarged, fragmentary, perspective view of the case of Fig. 6 with the cover opened to expose the encased game equipment.

The game equipment includes one or more, and preferably nine, "holes." One such hole 10 is shown in Fig. 1 and includes an open-bottomed box-like structure 12 having a roof 14 and four similar side walls 16 depending perpendicularly therefrom. Each side wall is provided with an arch-shaped opening 18 cut in from its lower edge and centered laterally in the side wall. The box structure is adapted to be used with a ball 20 preferably of golf-ball size, and accordingly is preferably four inches in height and six inches square, with openings three inches each in width and height.

Box structures formed from plywood have proved very satisfactory as elements of the game apparatus. However, other materials may be employed without departing from the scope of my invention. These other materials include other forms of wood, metal sheet or screen materials, stiff paper, molded plastic or rubber and the like.

Each hole includes also a flag staff 22 and a numbered flag 24 attached to the upper end thereof. The flag staff preferably takes the form of a wooden rod $\frac{3}{8}$ " in diameter and 36" long, although other materials as well as other dimensions may be employed. The flag staff 22 is removably carried within a cylindrical bore 26 provided centrally in the roof 14 of the box structure, and extends vertically within and above the box structure to support and display the flag 24. The flag 24 comprises a rectangle of cloth or other flexible material, carrying a numeral which serves to identify the goal.

When the hole is positioned on soft ground, the base end 28 of the flag staff may be forced a short distance into the ground to assist in anchoring the goal in position as well as to assist in retaining the flag staff in a vertical position (see Fig. 2). When the hole is set up indoors or is resting on ground which does not permit the flag staff to be projected into it, the base end 28 of the flag staff may simply rest upon the ground or floor surface. Even without being projected into the ground, the flag staff is held with substantial rigidity in vertical position by reason of the thickness of the material from which the roof is fashioned, as well as by the frictional abutment of the base end 28 of the flag staff with the floor or ground.

The playing ball 20 for the game comprises preferably a commercially available golf "practice" ball. Preferably the ball is one formed as a foraminous hollow sphere formed from plastic material. This ball has a diameter the same as a standard golf ball, namely about $1\frac{1}{8}$ ", and is characterized by its lightness in weight and resistance to being propelled for lengthy distances. However, the playing ball may also take the form of a standard golf ball or other ball dimensionally suited to the box structure.

Any suitable form of club for stroking the ball may be used, including a conventional golf club. Preferably, I employ a club of very simple and inexpensive construction, one of which is shown in Fig. 4. While one club is sufficient, I prefer to include as components of the game set or equipment a plurality, for example six, similar clubs so that each player may be furnished a club.

The club 30 comprises a head 32 having the general form of an elongate rectangular block, and a shaft 34

fixedly connected to the head. The means for connecting the shaft to the head preferably include a cylindrical bore 36 in the head adapted to snugly accommodate one end of the shaft 34, and suitable means retaining the shaft within the bore, such as a dowel or pin 38 projected transversely through the head and the shaft.

The head 32 and the shaft 34 are so positioned relatively, that when the club 30 is held in playing position by a game participant, the shaft will be in a position intermediate the horizontal and the vertical, while the base of the head rests flat on the ground. Since the game ordinarily will be played in a relatively small area and will simulate play on a golf green, the club is preferably formed with no "loft" or particular provision for raising the playing ball off the ground. Accordingly two opposed vertical faces of the head constitute striking faces 40 for either a right or left handed swinging stroke at the playing ball.

The small size and light weight character of the playing ball require only a club 30 comparably light in weight. Therefore, the club may economically be fashioned of wood, with a hardwood, such as oak, being preferred for the head. However, it is to be understood that other materials, such as metal or plastic may also be used for either or both the head and the shaft. A club head four inches long, two and one-half inches high, and one and one-half inches thick has proved satisfactory for use with the golf practice ball hereinabove described, while a shaft $\frac{3}{4}$ inch in diameter and 28 inches long provides a suitable handle therefor.

Preferably a complete set of my game apparatus comprises nine holes, having flags numbered successively from one to nine, six clubs and six balls, thereby enabling from one to six participants to play the game at one time. Provision is made for compactly encasing this set and to this end a case 42 is provided which is formed from a suitable material such as plywood, metal or box-board, and is adapted to receive the hole box structures, the flag staffs, the clubs and the balls. A rectangular case 42 having internal dimensions of 36 inches in height, 8 inches in depth, and $10\frac{1}{2}$ inches in width provides an excellent container for the preferred set of my game equipment. The set of equipment is packed in the case by withdrawing the flag staffs from their respective box structures, and stacking the box structures one on top of another within the case. Ample room is thereby provided for inserting the flag staffs, the clubs and the balls inside the case alongside the stacked box structures.

Access to the interior of the case 42 is provided by forming the latter from two complementary scoop-shaped sections 44 and 46, which are pivotally connected together by a hinge 48. The hinge 48 is so positioned as to permit one case section 44 to be pivoted away from closing relationship with the complementary section 46 to expose the interior of the case. A suitable fastener or lock 50 is provided to releasably hold the two sections 44 and 46 together, while suitable handle means 52 are provided on the case to facilitate its handling.

The game is preferably played by from one to six participants whose object is to strike at the ball with the club to propel it toward and into each goal successively in as few total strokes as possible.

The game equipment is set up for play out of doors by placing a flag staff in each box structure and placing the assembled holes on a playing surface in any desired locations, preferably spaced apart, so as to lay out or establish a playing course. The holes may be placed any distance apart depending on the space available, and may be placed as to have natural or artificial barriers or obstacles, such as trees, bushes, tall grass, ponds, furniture and the like interposed between successive holes. If the ground permits, the base ends of the flag staffs are forced a short distance into the ground as hereinabove explained.

Space permitting, a game course set up out of doors

preferably has holes spaced sufficiently from successive holes to permit participants at least one hard stroke at the ball with the club prior to any necessary gentle, more accurate strokes to propel the ball into a hole.

5 Due to the propulsion-resistant characteristics of the golf practice ball, which rarely will travel a distance exceeding 25 feet, a distance of about 25 to 30 feet between goals is preferred. Obviously, even goals spaced successively at these intervals may be placed so that they all lie within a relatively small area, with a path between two goals crossing one or more other paths.

10 When the game apparatus is set up for indoors play, the distances between holes are preferably short, and the base ends of the flag staffs merely rest on the floor. 15 Full or strong strokes at the balls with the clubs are restricted, and the game is played employing gentle strokes, similar to "putting" in the game of golf.

15 It can be seen that I have provided a novel game and equipment by which it is played. It is played with a 20 golf-type swing of a club at a small, light-weight ball with the object of propelling that ball into a hole. However, neither the relatively expensive golf equipment nor the skill required to use it are needed to play the game.

25 Furthermore, the holes are adapted to be quickly and easily laid out or picked up as desired, and may be set up both indoors as well as out of doors with equal facility. The provision of several similar holes each 30 usable independently of the others, as well as the freedom of the holes from requiring placement in a definite, inflexible relationship or course, imparts a high degree of flexibility to the game, especially since the holes are adapted to rest on the playing surface without requirement of digging or cutting into that playing surface.

35 Each individual hole is a sturdy and compact structure which economically simulates a golf hole toward which a playing ball must be accurately directed. Furthermore, the structure of the holes is such that a set of holes may be compactly and conveniently encased when not being used, thereby lending itself not only to family use and enjoyment, but to use by playground and recreational departments as well.

40 My game equipment provides great enjoyment for participants by including an opening in each side box wall of the structure so as to form a substantially omnidirectional golf hole. Each hole is adapted to present a symmetrical and attractive target toward which to direct a playing ball by the formation of each opening as to be centered laterally in a side wall, and by the provision of a vertical flag staff projecting centrally from the box structure. Not only does the flag staff present an attractive object toward which to line up a playing shot, but it also furnishes an identification means for each hole in golf manner.

45 55 The base end of the vertical flag staff projecting through the box structure serves to make the latter more effective as a golf hole, for by its central position in the box structure the base end constitutes an obstruction interposed midway between complementary openings in the side walls. The base end of the flag staff serves substantially to retain a ball within the hole once it is propelled thereinto by preventing the ball from being driven straight through the box structure in and out of complementary openings.

60 65 I claim:

1. A game equipment comprising a hole structure adapted to be placed on a playing surface and a playing ball adapted to be propelled thereinto, said structure including a box-like member having a roof and four side walls depending therefrom in rectangular formation, each side wall having an unobstructed opening midway between its ends and extending through its lower edge of a width greater than but less than twice the diameter of said ball and adapted to pass said ball freely there-through, the roof having a vertical aperture centrally

thereof, and an elongate rod removably projected through said aperture perpendicular to the playing surface, the lower end of said rod extending at least to the playing surface and being disposed in alignment with all of said openings to thereby obstruct movement out of one of said openings of the ball when the latter has entered the structure through an oppositely disposed opening.

2. A game equipment comprising a hole structure adapted to be placed on a playing surface and a playing ball adapted to be propelled thereinto, said structure including a box-like member having a roof and four side walls depending therefrom in rectangular arrangement, each side wall having an unobstructed opening in its lower edge midway between its ends and extending through its lower edge of a width greater than but less than twice the diameter of said ball and adapted to pass the ball freely therethrough and an elongate rod carried by and extending downwardly from said roof centrally thereof at least to the playing surface and perpendicular thereto, said rod being disposed in alignment with all the said openings to thereby obstruct movement of the ball out of one of said openings when the latter has entered the structure through an oppositely disposed opening.

3. A game equipment comprising a hole structure adapted to be placed on a playing surface and a playing

5

ball adapted to be propelled thereinto, said structure including a box-like member having a roof and a continuous side wall depending therefrom, said side wall having a plurality of peripherally spaced, unobstructed openings therein extending through its lower edge of a width greater than but less than twice the diameter of said ball and adapted to pass the ball freely therethrough, said openings being equally spaced and each opposite and in alignment with another of said openings, a vertically disposed elongate rod carried by said roof and extending vertically downwardly therefrom to the playing surface and perpendicular thereto, said rod being disposed in alignment with all the said openings to thereby obstruct movement of the ball out of one of said openings when the latter has entered the structure through an oppositely disposed opening.
